METHOD OF SWEETENING HYDROCARBON DISTILLATES

Virden W. Wilson, Buffalo, N. Y., assignor to Buffalo Electro-Chemical Company, Inc., Buffalo, N. Y.

Application March 4, 1937, Serial No. 123,011

10 Claims. (CL 196—29)

This invention relates to the sweetening of hydrocarbon distillates and more particularly to sweetening of such distillates by the use of caustic solutions of methanol in conjunction with materials evolving hydrogen peroxide in solution.

In a copending application, Ser. No. 123,481, it has been pointed out that substantially water free alcoholic solutions of caustic alkalies and hydrogen peroxide used in conjunction are effective sweetening agents for hydrocarbon distillates, the higher and less acidic mercaptans as well as the lower and more acidic mercaptans being effectively and completely removed by treating the sour hydrocarbons with a substantially water free solution of caustic alkali in a water soluble alcohol, thereby changing the mercaptans to mercaptides and oxidizing the mercaptides to innocuous disulfides soluble in the distillate.

The present invention relates specifically to the use of methanol solutions of caustic alkali wherein substantial amounts of water may be present, this solution being used in conjunction with hydrogen peroxide for the sweetening of hydrocarbon distillates that are designated as "sour" and, therefore, contain sulphur as mercaptan or as hydrogen sulfide.

It is an object of the present invention to provide a method for sweetening hydrocarbon distillates wherein an aqueous methanol solution of caustic is agitated with the distillate to be sweetened and wherein separation of the distillate and the alcoholic solution is readily secured without the necessity of adding large quantities of water and wherein, therefore, a large steam consumption for alcohol recovery is eliminated.

In the drawings Fig. 1 is a flow sheet illustrating the procedures of the present invention. Fig. 2 is a graph of the effect of aqueous methanol-caustic solutions and hydrogen peroxide upon heptyl mercaptan. Fig. 3 is a graph showing the location of sulfur in a sample of unsweetened washed gasoline and Fig. 4 is a graph showing the location of the sulfur in a sweetened solution of the crude of Fig. 3.

In general, therefore, it has been determined in accordance with the procedures of the present invention that a solution of sodium or potassium hydroxide or other caustic alkali in methyl alcohol containing from about 30 to 50 grams, more or less, of caustic alkali per liter of alcohol, when used in conjunction with sufficient hydrogen peroxide, to react with the mercaptans present in the hydrocarbon distillate to be treated, will con-

vert substantially all the mercaptans therein to the corresponding organic disulfides, thus effecting sweetening of the sour hydrocarbon distillates.

The treatment may be effected by agitating the methanol-caustic solution with the distillate and the hydrogen peroxide. The period of contact between the solutions will vary in accordance with the manner of treatment, in general, the more vigorous the agitation the more intimate the contact of the solutions, the more rapid the sweetening. Upon completion of the agitation, a considerable portion of the methanol solution of caustic alkali will separate from the distillate and this may be withdrawn and reused without further treatment since the disulfide, produced by the oxidation of the mercaptide will be found in the hydrocarbon. A further quantity of alcohol may be recovered, if desired, from the hydrocarbon layer by washing this layer with a comparatively small quantity of water whereupon the methyl alcohol is removed substantially quantitatively, and as will be pointed out more fully hereinafter, this alcohol may be used in the preparation of further quantities of methanol caustic solutions.

As an example of the efficacy of the procedure of this invention, a synthetically sour gasoline was made from an unleaded, uncolored and sweet gasoline by adding heptyl mercaptan there-to and treating 100 cc.'s of the synthetically soured gasoline with 10 cc.'s of a methyl alcohol normal caustic solution and 0.2 cc.'s of hundred volume hydrogen peroxide.

Table I

Time of treatment	Percent sulfur as mercaptan	Percent converted or removed
1 min.	0.0727	None
2 min.	0.0034	95.2
3 min.	0.0012	98.3
5 min.	Trace.	99.9
	Sweet.	100

With methanol normal caustic 5 minutes agitation, the solution was sweet and all the mercaptan had been completely converted or removed.

Synthetically soured gasolines were prepared by adding propyl, butyl, and amyl mercaptans respectively to a sweet gasoline and these sour gasolines were completely sweetened by the use of methanol normal caustic alkali and hydrogen

peroxide treatment in a contact time of less than ten minutes as shown in Table II.

Table II

Mercaptan added	Original percent sulfur as mercaptan	Time of treatment	Percent sulfur remaining as mercaptan	Percent converted or removed
Propyl.....	0.1037	10	0.000	100
Butyl.....	0.1184	10	0.000	100
Amyl.....	0.1029	10	0.000	100
Heptyl.....	0.1033	10	0.000	100

15 As has been shown above, the lower molecular weight mercaptans are the more readily removed and to show the effect of the presence of water in the methanol-caustic solution, a gasoline synthetically soured with heptyl mercaptan was treated with aqueous methanol normal caustic of varying percentages of water by volume with the results set forth in Table III and in the graph in Fig. 2. It will be noted that with percentages of water above about 40 volume percent very little sweetening action is observed. As shown in the graph, the curve rises steeply and at about 60 volume percent of methanol conversion occurs. In each case the caustic concentration was maintained at 40 grams per liter of solution. A 30 100 cc. sample of the synthetically soured gasoline was treated for 10 minutes with 10 cc. of the treating solution and 0.2 cc. of 100 volume hydrogen peroxide.

Table III

Volume percent methanol alcohol	Percent sulfur remaining as mercaptan	Percent converted or removed
Original mercaptan.....	0.0717	None.
100%.....	0.000	100.0
75%.....	0.0019	97.3
50%.....	0.0366	49.1
25%.....	0.0454	36.5
5%.....	0.0610	15.0
Water.....	0.0652	9.0

45 In the copending application enumerated above it was shown that substantially water free water soluble mono-hydric alcohols containing caustic were effective in changing mercaptans to mercaptides, the latter being oxidized to disulfide by hydrogen peroxide or a substance liberating hydrogen peroxide. All of these alcohols form constant boiling mixtures with water except methyl alcohol. In the instant invention, methyl alcohol which does not form a constant boiling mixture with water, may be used together with water in solutions containing above about 60 percent by volume of methyl alcohol as the solvent for the caustic alkali such as sodium or potassium hydroxide or other caustic alkali capable of forming mercaptides as the treating solution. The greater the amount of water originally present in the methanol solution the lesser the quantity of methanol remaining in the distillate after agitation of the aqueous-methanol-caustic solution therewith and minimal quantities of wash water are needed to extract the residual methanol from the distillate.

70 Although synthetically soured gasolines are representative of sour gasoline encountered in the field, and sweetening procedures found successful upon gasoline containing the higher mercaptans can be used in refinery practice, a cracked distillate was treated as below.

75 A sample of a sour West Texas crude cracked

gasoline, representative of the worts type of sour gasolines made in the United States was treated successfully by agitating the gasoline with a methanol-caustic solution and the appropriate amount of hydrogen peroxide.

Table IV

Time of contact, minutes	Treating solution N caustic in methanol	Percent sulfur remaining as mercaptan	Percent removed or converted	10
Original gasoline.....	0.1 cc.	0.0782	90.2	
10.....	100 vol. H ₂ O ₂	0.0075		
10.....	0.2 cc.	Trace	99.9	
10.....	100 vol. H ₂ O ₂	0.0068	91.0	
10.....	0.2 cc.	0.0032	95.8	
10.....	50 vol. H ₂ O ₂	0.0032		
10.....	0.3 cc.	Trace	99.9	20
10.....	50 vol. H ₂ O ₂	0.000	100.0	
10.....	0.5 cc.	0.000		
10.....	50 vol. H ₂ O ₂	0.000		

25 The action of methanol-caustic-peroxide is a true sweetening of the sour West Texas cracked distillate as shown by the results set forth in Table IV. The crude gasoline was distilled through a fractionating column and succeeding fractions of 10% collected and the total sulfur and mercaptan sulfur determined. Another 30 sample was agitated with methanol-caustic-peroxide for 10 minutes and then fractionated and the total sulfur and mercaptan sulfur determined on each fraction.

35 The sulfur content of the original crude gasoline before sweetening was found to be 0.2760% sulfur by weight; the mercaptan content 0.0787% by weight. The graph of the sulfur content of the various fractions is shown in Fig. 3. An integration of this graph shows the sulfur content 40 to be 0.282% by weight, a figure in good agreement with that found by tests.

45 After sweetening, the sulfur was found to be 0.2555% Fig. 4. The fractions are shown by integration to contain 0.2490% sulfur by weight, 45 also the amount of sulfur in the still bottoms or residue is appreciably higher in the case of the sweetened gasoline than was found in the original sour gasoline. The table also shows that the sulfur has shifted toward the high boiling end, as would be expected by conversion of mercaptan to disulfide.

55 Although for purposes of illustration in the examples, hydrogen peroxide has been employed to oxidize the mercaptides to disulfides, other substances generating or liberating hydrogen peroxide in solution may be substituted in equivalent quantities, for instance, sodium peroxide, the perborates, percarbonates, persilicates and the like.

60 Referring to Fig. 1 of the drawings, cracking still products which have been passed through a hot oil separator 10 for removal of the liquid products and subsequently stabilized for the removal of propane and hydrogen sulfide are first contacted with a solution of caustic soda containing 15 to 20% sodium hydroxide as will be discussed later. A portion, if not all of the caustic soda necessary for this initial treatment may be obtained as bottoms from the methanol recovery still. This aqueous caustic treatment carried out 70 on the sour stabilized cracked gasoline will remove the more acidic mercaptans and will reduce the sulfur content of the gasoline in proportion to the amount of low boiling mercaptan present in the cracked stock. The caustic-washed gasoline 75

is then pumped through a mixing pump 12 either into a pipe coil or into a large turbulence pipe equipped with staggered orifice plates. At the mixing pump a predetermined amount of methanol caustic containing sufficient sodium hydroxide to react with all of the mercaptans present in the gasoline is added through one feed line into the pump, while an amount of concentrated hydrogen peroxide sufficient to insure complete sweetening is added concurrently by means of a proportioning pump or other suitable methods. Such a procedure has been found to yield better results than contacting the alcoholic alkalies and hydrogen peroxide in series, although such a procedure is entirely possible if advantages for this operation could be shown in plant operation.

The product discharged from the pipe coil or mixing chamber 13 consists of a fine dispersion of alcoholic caustic in the gasoline together with small quantities of hydrogen peroxide which have not reacted. For economic reasons it is desirable to keep this amount of free peroxide at a minimum. The dispersion of caustic and gasoline is discharged into a settling tank 14 where a considerable proportion of the alcoholic caustic settles to the bottom and may be withdrawn for recirculation through the mixing pump and the pipe coil. The quantity of methanol separating at this point will depend upon the concentration of water in the original methanol solution. The upper layer in the settling tank 14 which contains the remainder of the alcohol and a small amount of sodium hydroxide in dispersion in the gasoline is then passed into a washing tank 15 where it is contacted with a vigorous scrubbing spray of water. The volume of water is kept as low as practicable to insure complete removal of the alcohol from the gasoline and separation of the aqueous layer without detrimental emulsion formation. The concentration of the alcohol in the lower aqueous layer which settles in the washing tank will vary from 10 to 50%, depending on the nature of the hydrocarbon from which the alcohol is removed. Such treatment will leave in the gasoline less than about one half of one per cent of the methanol employed for the treatment, providing the mixture has been properly water washed. The upper layer from the wash tower is then passed through a small settling tank 16 where any further alcohol-water mixture dispersed in the gasoline will be removed by gravity settling. In certain cases it may be advantageous to eliminate this second settling tank if good separation occurs in the primary water washer. In general, the inclusion of this second settling tank will be desirable. From time to time the bottoms from this settling tank are drained into the primary aqueous settling tank discharge line and any alcoholic content of the settling tank bottoms is recovered in the usual manner. The water-washed gasoline from which all traces of the treating reagents have been removed, is then run directly to storage without the customary 24 to 48 hour settling period necessitated in the doctor treatment for removal of the finely dispersed lead sulfide sludge.

The alcohol extracted by the water wash is then pumped through a series of heat exchangers 17 to a bubble plate fractionating column 18. The overhead from this alcohol fractionating column is condensed in a set of heat exchangers 18 to affect maximum heat recovery. The recovered methanol is run to storage 19 from which it can be pumped to mixing tanks where fresh alcoholic caustic is made up in quantities sufficient to in-

sure adequate caustic supply at the primary mixing pump at all times. The aqueous solution of caustic soda obtained as bottoms from the fractionating column may be discarded or may be used in the primary cracked gasoline caustic washers as mentioned in the preceding paragraph of this discussion. The process of treating and alcohol recovery is made cyclic in this manner and the amount of alcohol required for continuous operation will remain substantially constant and need be replaced only as fractionating losses, or gasoline carry-over losses become appreciable.

What is claimed is:

1. The method of sweetening sour hydrocarbon distillates which comprises treating the liquid distillate with a methanol solution of a caustic alkali and water, and an oxidizing agent capable of liberating hydrogen peroxide.

2. The method of sweetening sour hydrocarbon distillates which comprises treating the liquid distillate with an oxidizing agent capable of yielding hydrogen peroxide, and a methanol solution of caustic alkali and water, the methanol being in greater amount than the water.

3. The method of sweetening sour hydrocarbon distillates which comprises agitating the liquid distillate with a methanol solution of caustic alkali and water, and an oxidizing agent capable of yielding hydrogen peroxide.

4. The method of sweetening hydrocarbon distillates containing mercaptans which comprises adding to the liquid distillate a methanol solution of caustic alkali and water, and a sufficient quantity of an oxidizing agent capable of yielding hydrogen peroxide to change the mercaptans to disulfides, agitating the mixture and separating the distillate and the methanol solution.

5. The method of sweetening hydrocarbon distillates containing mercaptans which comprises adding to the liquid distillate a methanol solution of caustic alkali and water and containing at least 60% by volume of methanol, and a sufficient quantity of an oxidizing agent capable of yielding hydrogen peroxide to change the mercaptans to disulfides, agitating the mixture, separating the distillate and the methanol solution, and thereafter adding a small quantity of water to the distillate to eliminate methanol therefrom.

6. The method of sweetening sour hydrocarbon distillates which comprises treating the liquid distillate with an aqueous solution of a caustic alkali and thereafter with a methanol solution of a caustic alkali and water, and an oxidizing agent capable of yielding hydrogen peroxide.

7. The method of sweetening sour hydrocarbon distillates which comprises treating the liquid distillate with an aqueous solution of a caustic alkali, separating the distillate from the aqueous caustic solution and thereafter treating the distillate with a methanol solution of a caustic alkali and water, and an oxidizing agent capable of yielding hydrogen peroxide.

8. The method of sweetening sour hydrocarbon distillates which comprises treating the liquid distillate with an aqueous solution of a caustic alkali, thereafter with a methanol solution of a caustic alkali and water, and an oxidizing agent capable of yielding hydrogen peroxide, and thereafter permitting the distillate and methanol solution to separate, and withdrawing the distil-

9. The method of sweetening sour hydrocarbon distillates which comprises treating the liquid distillate with an aqueous solution of a caustic alkali, thereafter with a methanol solution of a caustic alkali, thereafter with a methanol solution of

4.

a caustic alkali and water, and an oxidizing agent capable of yielding hydrogen peroxide, separating the distillate from the mixture and subjecting it to a water wash.

5 10. A method of sweetening sour hydrocarbon distillates which comprises treating the liquid distillate with a methanol solution of a caustic

alkali and water, and hydrogen peroxide, permitting the mixture to settle and separate into an upper layer of distillate and a lower layer of methanol caustic solution and withdrawing the lower layer.
